UNITED STATES PATENT OFFICE

ADAM J. GEORGE, OF KENNETT, MISSOURI

SHIRT COLLAR SETTING DEVICE

Application filed May 29, 1930. Serial No. 457,222.

This invention relates to a shirt collar setting device particularly adapted for use in shirt factories and laundries for shaking or setting the attached collars on shirts and blouses during the ironing or pressing operation and has for one of its important objects to provide, in a manner as hereinafter set forth, a device of this character embodying a novel construction and arrangement of parts whereby the same is adapted for use on shirts having attached collars of any size thereon.

Another important object of the invention is to provide a shirt collar setting device of the aforementioned character embodying means for holding the shirt or blouse in position on the pressing or ironing table, said means permitting the shirt to be expeditiously turned over when desired during the pressing or ironing thereof.

A further important object of the invention is to provide a shirt collar setting device of the character described of a construction whereby the proper positioning of the collar thereon is expedited and the invention aims still further to provide a device of this character which constitutes a gauge for checking the size of the collar.

Still further objects of the invention are to provide a device of the character set forth which will be simple in construction, strong, durable, efficient in its use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in top plan of the shirt collar setting device constructed in accordance with this invention in operative position in a collar, said collar being indicated in broken lines.

Figure 2 is a view in top perspective showing the position of the collar setting device on an ironing or pressing table.

Figure 3 is a detail view in perspective showing the hinged supporting means upon

which the collar setting mechanism of the device is detachably mounted.

Figure 4 is a view in front elevation of the device.

Figure 5 is a view in side elevation.

Figure 6 is a view in top plan of the collar setting mechanism detached from the supporting means.

Referring to the drawings in detail, it will be seen that the reference numeral 1 designates a hinge leaf which is secured at the desired point on the ironing or pressing table 2 through the medium of the anchoring screws 3, said hinge leaf being provided with a vertically offset portion 4 to which is hingedly connected the leaf 5 having the flange 6 thereon for abutting engagement with the flange 7 formed integrally on a plate 8 and which is rotatably supported on the hinge leaf 5 through the medium of the pivot screw 9. The plate 8 has mounted thereon the upstanding pins 10 and is further provided with a threaded opening 11.

A plate 12 has formed therein the openings 13 (see Figure 6) for the reception of the pins 10 for detachably connecting said plate 12 to the plate 8. An anchoring screw 14 extends through the rear end portion of the plate 12 and is threaded into the opening 11 of the plate 8 for securing said plate in position on the pins 10. Mounted on the upper side of the plate 12 in spaced relation thereto is a guide plate 15 which extends from the rear ends thereof to the sight opening 16 in said plate. It should be here stated that the plate 15 conforms in shape to the configuration of the plate 12 and that the pins 10 project slidably through said plate 15 and the anchoring screw 14 also extends therethrough. Recesses 17 are formed in the opposite side of the guide plate 15. Collar setting or shaping plates or bars 18 are mounted for sliding movement in opposite directions between the plate 12 and the guide plate 15 and have turned backs or rolled free end portions 19 providing the sloping ends 20 for engagement with the shirt collar. Retaining ribs 21 are provided for preventing the collar from slipping on the bars 18. A graduated ratchet disk 20' is rotatably

85
90
95
100

mounted on the guide plate 15 and is operatively connected to the bars 18 through the medium of the actuating links 19' which travel in the recesses 17 provided therefor in said guide plate 15. A substantially inverted U-shaped handle 22 is mounted on the disk 20' for rotating the same in a manner to slide the bars 18 outwardly in opposite direction and against the tension of a coil 10 spring 23 having its opposite ends anchored to the links 19' in a manner to yieldingly draw the same together to return the bars 18 to retracted or inoperative position. The disk 20' is mounted for rotation on the guide plate 15 through the medium of the pivot screw 23'.

A pawl 24 is pivotally mounted on the guide plate 15 for operative engagement with the ratchet teeth on the periphery of the disk 20' for retaining the bars 18 in extended or operative position against the tension of the coil spring 23.

A spring 25 is operatively engaged with the pawl 24 in a manner to releasably maintain said pawl in engagement with the teeth of the disk 20'. The free end of the pawl 24 has formed thereon a finger piece 26 to facilitate the operation of said pawl.

Mounted for longitudinal adjustment on the substantially V-shaped forward end portion of the plate 12 which projects beyond the guide plate 15 is a slotted plate 27 having projecting therefrom the headed stud 28 for engagement in the crotch formed at the front 35 of the collar when the ends thereof are brought together, as best illustrated in Figure 1 of the drawings. The plate 27 is adjustably mounted on the plate 12 through the medium of the screws 29. An indicating 40 mark 30 is provided on the guide plate 15 for co-action with the graduations 31 on the disk 20' to determine and regulate the extent of movement of the bars 18.

In use, the shirt is laid on the ironing or 45 pressing table with the front side of said shirt up and with the collar disposed at a point adjacent the setting device. The plate 12 is then raised slightly and the collar is moved to the desired position thereover. The 50 front of the collar is then inserted under the stud 28 in the manner best illustrated in Figure 1 of the drawings. The disk 20' is then rotated in a clockwise direction through the medium of the handle 22 in a 55 manner to move the bars 18 outwardly in opposite direction through the medium of the links 19' and against the tension of the coil spring 23. As the ends 20 of the bars 18 engage with the collar and as the front of 60 the collar is secured under the stud 28, said collar will be forced to assume a substantially triangular shape or a wedge shape. The collar is then clamped in the desired position and the body of the shirt may then be 65 ironed. It may be well to here state that it

is the general practice to press attached collars flat before folding the same and it is therefore unnecessary to press or iron the collar after it is mounted on the setting device.

As the ironing or pressing of the front of the shirt progresses and the pressing iron comes to that part of the shirt adjacent the lower edges of the rolled back portion 19 of the bars 18 there will be found a surplus 70 of material as in all shirts, whether or not this device is used, and this surplus is done away with by simply running the edge of the pressing iron up to and under the device, the plate 12 being raised, and this surplus is 75 folded under the collar, as is also the usual method. The aforementioned surplus of the material is at the point in the shirt where the shoulder seams enter the collar band.

From this point there are three methods of 80 using the device. One method is to remove the shirt from the device by disengaging the pawl 24 from the ratchet disk 20 in a manner to permit the retraction of the bars 18 and after the shirt is removed the device 85 is swung over on the hinge leaf 1 where it is 90 out of the way and the ironing of the shirt, insertion of the usual card, etc. is completed in the usual manner. The second method of 95 using the device is to remove the plate 12 from the plate 8 by unscrewing the screw 14 after which said plate 12 may be lifted from the pins 10. When it is desired to turn the shirt over the setting mechanism is left 100 in place therein and simply lifted from the plate 8 and turned over with the shirt after which the operation is finished. After the shirt is finished, the same is again turned face up with the setting mechanism still in place therein and said setting mechanism is then placed over the pins 10 which secure the plate 12 and the pawl 24 is then disengaged 105 from the ratchet disk 20 to permit the retraction of the bars 18.

The third method is similar to the second 110 method except that the setting mechanism, with the shirt in position thereon, is raised on the hinge 4 and said setting mechanism is then rotated on the screw 9 to reverse the shirt on the table.

As best seen in Figures 4 and 8 of the drawings, a lug 32 depends from the longitudinal center of the plate 12 for the purpose of indicating the center of the collar when the shirt is being folded. The opening 120 16 provides means whereby the label in the collar may be observed to facilitate the centering of the collar on the device.

It is believed that the many advantages of 125 a shirt collar setting device constructed in accordance with this invention will be readily understood, and although the preferred embodiment of the invention is as illustrated and described, it is to be understood that changes in the details of construction may 130

be had which will fall within the scope of the invention as claimed.

What is claimed is:—

1. A shirt collar setting device of the character described comprising a plate, a stud mounted for longitudinal adjustment substantially on the longitudinal center of the plate, a pair of collar engaging bars mounted for lateral sliding movement in opposite directions on the plate, and means for simultaneously moving the bars.

2. A shirt collar setting device of the character described comprising a substantially flat plate, a stud mounted for longitudinal adjustment substantially on the longitudinal central portion of the plate adjacent one end thereof, said stud engageable with the front portion of the collar in a manner to anchor said collar, a pair of collar engaging bars mounted for lateral sliding movement in opposite directions on the plate rearwardly of the stud and adapted to project beyond the opposite sides of said plate, a disk rotatably mounted on the plate, actuating links operatively connecting the collar engaging bars to the disk for actuation thereby upon rotation of said disk, resilient means for returning the bars to retracted position, means engageable with the disk in a manner to retain the bars in shifted position.

3. A shirt collar setting device of the character described comprising a substantially flat plate for insertion in the collar and having a sight opening therein, a stud adjustably mounted for longitudinal movement on the plate forwardly of the sight opening and adapted for engagement with the front portion of the collar in a manner to anchor the same, a guide plate mounted in superposed spaced relation on the first named plate rearwardly of the sight opening, a pair of collar engaging bars slidably mounted for movement in opposite directions between the guide plate and the first named plate and adapted to project beyond the opposite sides of said first named plate, a disk rotatably mounted on the guide plate, links operatively connecting the collar engaging bars to the disk for actuation thereby upon rotation thereof, a handle for rotating the disk in a manner to move the bars to operative position, a coil spring connected to the links in a manner to yieldingly urge the same and the bars to retracted position, ratchet teeth on the periphery of the disk, a spring controlled manually operable pawl pivotally mounted on the guide plate and engageable with the ratchet teeth in a manner to releasably secure the disk against rotation in one direction, a connecting hinge for swingably mounting the plate on the pressing table, means for detachably securing the plate on the connecting hinge, the collar engaging bars terminating, at their free ends, in turned back portions providing rounded collar engaging surfaces, retaining ribs mounted on said collar engaging surfaces, said surfaces being sloped, and coacting indicating marks on the guide plate and the disk.

plate forwardly of the sight opening and adapted for engagement with the front portion of the collar in a manner to anchor the same, a guide plate mounted in superposed spaced relation on the first named plate rearwardly of the sight opening, a pair of collar engaging bars slidably mounted for movement in opposite directions between the guide plate and the first named plate and adapted to project beyond the opposite sides of said first named plate, a disk rotatably mounted on the guide plate, links operatively connecting the collar engaging bars to the disk for actuation thereby upon rotation thereof, a handle for rotating the disk in a manner to move the bars to operative position, a coil spring connected to the links in a manner to yieldingly urge the same and the bars to retracted position, ratchet teeth on the periphery of the disk, a spring controlled manually operable pawl pivotally mounted on the guide plate and engageable with the ratchet teeth in a manner to releasably secure the disk against rotation in one direction, a connecting hinge for swingably mounting the plate on the pressing table, means for detachably securing the plate on the connecting hinge, the collar engaging bars terminating, at their free ends, in turned back portions providing rounded collar engaging surfaces, retaining ribs mounted on said collar engaging surfaces, said surfaces being sloped, and coacting indicating marks on the guide plate and the disk.

In testimony whereof I affix my signature.

ADAM J. GEORGE.
